W. V. BLACK

DISPENSING BIN

Filed Sept. 20, 1927

INVENTOR
William V. Black,
by Edward A. Lawrence
his attorney.

UNITED STATES PATENT OFFICE.

WILLIAM V. BLACK, OF PITTSBURGH, PENNSYLVANIA.

DISPENSING BIN.

Application filed September 20, 1927. Serial No. 220,821.

More particularly, my improved dispensing bin is designed for coal and like fuel, and the object which I have in view is the provision of a dispensing bin of improved design and construction, into which the contents are introduced at the top and removed as required from the bottom through a doorway in the front of the bin.

Novel features of construction, and also 10 of arrangement of parts will appear from the following description.

In the accompanying drawings, wherein I have illustrated the best embodiment of the principles of my invention now known 15 to me, Fig. 1 is a front elevation of the bin, the door being shown open; Fig. 2 is a vertical section thereof taken in a plane at right angles to that of Fig. 1, the door being shown open; Figs. 3 and 4 are sectional 20 views taken respectively along the lines 3—3 and 4—4 in Fig. 2; Fig. 5 is a detail on enlarged scale and taken in section like Fig. 2, the door being shown open, and Fig. 6 is a similar view with the door closed.

25 My improved bin is in the form of a box which may be made of any suitable material, but preferably of metal as indicated in the drawings.

The bin is vertically elongated and its 30 dimensions depend upon the manner in which it is to be used. Thus the bin may be situated in the cellar and of sufficient size and capacity to hold a supply of fuel for a house furnace for an extended period, 35 or the bin may be sufficiently small to be placed in a room to contain a supply of fuel for a smaller fire and for a shorter period. The bin is preferably rectangular in form.

Referring to the drawings, 1 is the bottom, 2 the side walls, 3 the back wall and 4 the front wall of the bin.

The top of the bin is provided with a filling opening 5 through which the supply of fuel is introduced into the bin, and 6 is the 45 lid or cover for said opening, the same being substantially dust-tight.

Near the bottom of the bin the latter is 50 provided with a displacement shelf which extends from the front wall and inclines downwardly and rearwardly toward the rear wall but stops short of the latter, thus leaving an opening 7 through which the fuel feeds downwardly by gravity as it is removed from below.

Where, as indicated in the drawings, the 55 bin is made of metal, the displacement shelf may be formed by cutting the metal of the front wall 4 to form the rectangular doorway 8 and bending the cut material inwardly as at 9 and supporting the bent-in 60 portion by a transversely disposed metal plate 10 whose ends are flanged as at 11 and riveted to the side walls 2 of the bin. The end of the metal 9 may be bent down around the inner edge of the plate 10 as shown at 12. 65

Extending inwardly from the lower edge of the doorway 8 is a false floor 13 which inclines downwardly toward the rear wall 3 of the bin and merges with the bottom 1 as shown in Fig. 2. The floor 13 is preferably 70 strengthened by being supported from below by the plate 14 whose ends are flanged as at 15 and riveted to the side walls 2.

Beneath the false floor 13 the aperture 75 which forms the doorway 8 is extended down to the bottom 1 of the bin to permit the insertion of the dust-drawer 16 which is designed to fit the space between the false floor 13 and serves to catch the dust which may descend between the false door and a 80 door closing the doorway 8.

A door of novel character is provided for the doorway 8, the same comprising a front door 17 having extending inwardly therefrom the side plates 18 of general triangular 85 shape and provided with edge flanges 19, which, when the door is open engage the side edges of the doorway 8 from within, limiting the outward movement of the door and supporting it in its open position. The 90 edges of said side plates 18 are cut away as at 20 to form straight surfaces which rest on the shelf 13 when the door is closed, thus supporting the door in its closed position.

The bottom edge of the door, when open, 95 mates with the front edge of the false floor and thus the front plate of the door forms a continuation of the false floor. At its bottom the door plate 17 is provided with a flange 21 which when the door is open fits 100 under the front edge of the false floor to seal the joint between the floor and the door. When the door is closed, as indicated in Fig. 6, this flange mates with the outwardly curved flange 22 at the top of the front 105 of the dust drawer. Thus any dust which might collect between the door and the false floor or upon the flange 21, will, as the

door is closed, be discharged down into the interior of the dust drawer instead of outside the bin.

5 A suitable handle 23 is provided for the lid 6, the door and the dust bin.

It is apparent that as the fuel is removed at intervals, as need requires, through the doorway 8, the mass of fuel above the inclined displacement shelf will automatically 10 feed down through the opening 7 so that a shovel may be introduced through the doorway 8 and the fuel removed.

The inclined false floor prevents the downwardly fed fuel from moving forwardly 15 against the door, causing the fuel to be held back out of the way but within convenient reach of the shovel. The door, when opened forms an outward extension of the inclined floor and is provided with side walls, thus 20 preventing such coal as may be spilled from the shovel, from dropping out into the room.

As the door closes any coal which may have been spilled thereon is dropped back into the bin.

25 The door requires no hinges and is therefore more durably mounted and is not liable to be choked against closing or opening by accumulations of fuel or dust therefrom.

The dust drawer collects such dust as may 30 descend between the false floor and a door closing the doorway 8, thus preventing accumulations of dust in portions of the bin which are inaccessible or difficult of access.

35 These features of advantage render the bin highly suitable for use in a room.

My improved bin is inexpensive, convenient for use and very durable.

What I desire to claim is:—

1. A bin for the purposes described comprising a box into which the material is 40 introduced through the top, and provided adjacent to its bottom with a rearwardly extending and downwardly inclined displace-

ment shelf with an opening between the shelf and the rear wall of the bin, an access aperture in the front wall of the bin below the displacement shelf, a door for said aperture, a false floor leading inwardly and downwardly from said aperture, and a removable drawer beneath the false floor to 50 catch the dust which may descend between the false floor and the door when closed.

2. A bin for the purposes described comprising a box into which the material is introduced at the top and having an access 55 aperture in the lower portion of the box, a downwardly and rearwardly inclined false floor whose front end horizontally intersects said access aperture, a door adapted to swing on its bottom edge and arranged when 60 open to form a continuation of said false floor, a dust drawer inserted into the box below the false floor, and means whereby dust allowed to drop by the closing of the door is received into said drawer.

65 3. A bin for the purposes described comprising a box into which the material is introduced at the top and having an access aperture in the lower portion of the box, a downwardly and rearwardly inclined false 70 floor whose front end horizontally intersects said access aperture, a door adapted to swing on its bottom edge and arranged when open to form a continuation of said false floor, a dust drawer inserted into the box below 75 the false floor, said door being provided with a flange which is arranged to extend under the front edge of the floor when the door is open, and an outwardly flaring flange on the top of the drawer front against which the door flange abuts when the door is closed, whereby the dust released by the closing of the door is dropped into the drawer.

80 Signed at Pittsburgh, Pa., this 19th day of Sept., 1927.

WILLIAM V. BLACK.
